REFRIGERANT VAPORIZER

Edward Heitman, Detroit, Mich., assignor to
 Kelvinator Corporation, Detroit, Mich., a corporation of Michigan

Application February 17, 1931, Serial No. 516,329

3 Claims. (Cl. 257—255)

This invention relates to refrigerating apparatus and more particularly to improvements in refrigerant vaporizers. It has for its principal object the provision of a refrigerant vaporizer of improved efficiency and embodying a novel combination of elements. The improved efficiency is obtained by providing the usual vaporizer coil with a plurality of sheet metal fins for increasing the heat transfer surface thereof, and by causing the refrigerant fluid flowing through the refrigerant coils to have a scrubbing or scouring effect on the interior walls thereof. The novel combination of elements comprises a plurality of U-shaped refrigerant pipes provided with sheet metal fins, means for connecting the refrigerant pipes in series to form a continuous coil, and means, responsive both to the variation of pressure within the coil and the temperature of the outlet end thereof, for admitting refrigerant to the coil.

A further object of the invention is the provision of a refrigerant vaporizer consisting of a plurality of refrigerant coils projecting through a plurality of sheet metal fins, which may be built in unitary sections and assembled to form a vaporizer of any desired size.

25 In the drawing:

Figure 1 is a side elevational view of a refrigerant vaporizer embodying the invention, shown in position in a refrigerator case.

Figure 2 is an end view in elevation of the structure shown in Figure 1;

Figure 3 is a cross sectional view of the thermostatically controlled expansion valve shown in Figures 1 and 2;

Figure 4 is a diagrammatic sketch of a refrigerant condensing unit; and

Figure 5 is a top plan view of the refrigerant vaporizer shown in Figs. 1 and 2.

The refrigerant vaporizer 10 embodying this invention is shown positioned in a refrigerated case 11. The case 11 has the usual outer wall 12 and inner wall 13 with insulation material 7 disposed between the walls. The vaporizer as illustrated in Figures 1 and 2 consists of a double row of sheet metal fin members 14. The fins are all substantially the same size and are spaced from each other at regular intervals. Each of the fins is provided with three pairs of vertically spaced openings 18. It should be understood, however, that the size of the fins and the number and position of the openings therein may be varied as desired. The fins in each row are aligned so that the openings in each fin will register with the openings in the adjoining fins. At intervals throughout the length of the double rows of fins 14, similar fins 15, of substantially twice the

length of the fins 14, are interposed between the fins 14. These larger fins are also provided with openings 18 to correspond with the openings in the fins 14. All of the openings 18 on one side of each of the fins 14 and 15 are surrounded with flanges 17 of somewhat smaller diameter than the openings 18. The two legs of a U-shaped refrigerant pipe 16 project through each pair of vertically spaced openings 18 in the fins 14 and 15 in each row. The pipes 16 are somewhat larger in diameter than the flanges 17 with the result that the flanges snugly engage the pipes. The flanges 17 may be soldered to the pipes 16 if desired. A good thermal contact is made however without soldering.

The U-shaped pipes 16 are positioned with their open extremities all at the same end of the vaporizer. All of these open ends with the exception of the extremity of an upper leg at one side of the vaporizer and a lower leg at the opposite side, are connected in series by couplings 19. The couplings 19 join together the alternate legs of adjacent pipes. In this manner the several refrigerant pipes 16 are made to form a continuous coil having open ends at its opposite extremities. The open end at the extremity of the upper leg is provided with a coupling member 22 adapted to receive one extremity of a suction line 23. The other extremity of the suction line is connected to the low side of a refrigerant compressor 24. As illustrated in Figure 2, a portion of the outer fin 14 adjacent the pipe extremity which is joined to the suction line may be cut away to provide a protected space for the coupling 22 and the thermostat bulb 52, if desired. The open end at the extremity of the lower leg of the pipe 16 at the opposite side of the vaporizer is connected to the discharge port of a thermostatically controlled expansion valve 20. The thermostat bulb 52 of the valve 20 is preferably held in thermal contact with the suction line 23 by means of a clamp 8.

The condensing unit 25, in addition to the compressor 24, consists of a motor 26, a condenser 28, and a liquid receiver 29. The motor 26 is adapted to deliver power to the compressor 24 by means of a belt connecting a rotating pulley on the motor 26 to the flywheel 27 of the compressor. The compressor, condenser and liquid receiver are operatively connected together in the usual manner. The liquid receiver 29 communicates with the expansion valve 20 by means of a refrigerant conduit 30.

The expansion valve 20 consists of a main body portion 31 and a housing 32. The body portion 31 is provided with a centrally disposed

chamber 33 and an inlet port 34 with which the liquid line 30 communicates through means of a pair of couplings 35 and 36. The port 34 communicates with the chamber 33 by means of a channel 36' and a valve opening 37. The valve opening 37 is closed by a needle valve 38 which is provided with an annular shoulder 40 and a guide rod 39. The valve is held in position to close the opening 37 by means of a spring 41 interposed between the collar 40 and an adjustable nut 42 threaded into the wall of the body portion 31. The body portion 31 is also provided with a discharge port 43 which communicates with the chamber 33 and is adapted to receive a coupling 44. The coupling 44 is adapted to engage a coupling 45 which is carried by the open extremity of the lower leg of the refrigerant pipe 16.

The housing 32 is securely connected to the body portion 31 and is divided into two compartments 46 and 47. An annular opening 48 provides communication between the two compartments. Communication is established between the chamber 33 and the compartment 46 by means of a channel opening 49. An expandible bellows 50 disposed in the compartment 46 surrounds the channel opening 49 and has its extremities secured in fluid tight contact with the outer wall of the body portion 31. A pair of push rods 57 projecting through openings in the wall of the body portion 31 provided for that purpose on opposite sides of the valve opening 37 are positioned between the end wall of the bellows 50 and the collar 40 carried by the needle valve 38. An expandible bellows 51 disposed in the chamber 47 has its interior in open communication with the thermostat bulb 52 through means of a flexible conduit 53. The pressure of the atmosphere surrounds both of the bellows.

A pin 54 disposed in the annular passageway 48 has its opposite extremities abutting the exterior walls of the bellows 50 and 51. A spring 55 encircling the pin 54 is compressed between the outer wall of the bellows 51 and an annular shoulder formed in the wall of the housing 32 around the annular passageway 48. The spring 55 exerts a pressure against the bellows 51 tending to resist the expansion thereof. A spring 56 disposed within the bellows is positioned between its opposite walls and is adapted to assist the internal expansion thereof. The compression of the spring 56 may be varied by the adjustment of a tubular adjusting member 9.

The expansion valve 20 controls the admission of refrigerant to the vaporizer 10 in the following manner. When the pressure within the vaporizer is less than the atmosphere the bellows 50 is partially collapsed by the atmosphere. This partial collapse of the bellows causes the pins 57 to push against the collar 40 and force the needle valve 38 away from the valve opening 37 which permits refrigerant to flow through the expansion valve into the vaporizer. If the temperature of the medium surrounding the thermostat bulb 52 is relatively high, the bellows 51 will be in an expanded position and accordingly assists the atmosphere in opening the valve 37. Under such a condition the valve 37 is opened when there is only a very slight difference between the atmospheric pressure and the pressure within the vaporizer. However, when the temperature of the medium adjacent the thermostat bulb is low, the bellows 50 is deprived of the assistance of the bellows 51 and a relatively great pressure difference between the atmosphere and the pressure

within the vaporizer 10 is necessary to open the valve. The refrigerating process is accordingly carried on at a higher suction pressure than would be possible if the conventional expansion valve were used. Substantial operating economies are effected by reason of this fact.

The thermostatically controlled expansion valve 20 admits liquid refrigerant into the lower leg of one of the outer pipes 16 of the vaporizer 10. The pathway which the liquid refrigerant must follow to reach the suction line 23 requires it to pass continually from the lower leg of a pipe to the higher leg and thence back to the lower leg of an adjacent pipe, until finally discharged from the higher leg of the last pipe into the suction line 23. This continuous circular movement of the refrigerant fluid from a lower to a higher level and back again prevents the fluid from flowing freely from the inlet to the outlet. The turbulence thus produced in the refrigerant fluid causes it to bombard the interior walls of the vaporizer coil continuously. As a result of this continuous bombardment the inner walls of the pipe 16 are kept relatively free from the film of oil and refrigerant which customarily collects thereon. The substantial removal of this film greatly increases the efficiency of the vaporizer.

The expanded refrigerant fluid is withdrawn from the vaporizer 10 through the suction line 23 by means of the action of the compressor 24 which compresses the expanded refrigerant and delivers it to the condenser 28. After being condensed the refrigerant fluid passes into the liquid receiver 29 where it again becomes available for use in the vaporizer 10. The refrigeration cycle is controlled by a conventional thermostat, not shown, which may be located in any desired position in the case 11.

Although the vaporizer 10 illustrated in Figures 1 and 2 consists of but two rows of sheet metal fins 14, joined together by means of the fins 15, it should be understood that any number of rows of fins 14 may be used together with fins 15 of appropriate size. The rows of fins are assembled as hereinafter described in sections and joined together to form a complete unit. This method of building refrigerant vaporizers in sections materially lessens the cost of building a complete line of vaporizers as well as greatly facilitates the manufacturing and handling thereof.

The preferred method of assembling the vaporizer illustrated in Figures 1 and 2, comprises placing a desired number of fins 14, which have previously been provided with openings 18, in a rack adapted to retain them in spaced relation to each other. A suitable number of the larger fins 15 are placed in the rack between the fins 14 and one edge of the fins 15 is aligned with the corresponding edge of the fins 14. The two legs of the necessary number of U-shaped refrigerant pipes 16 are then projected through all of the openings 18 in the fins 14 and 15 while they are in the rack. The refrigerant pipes 16 are, of course, selected of proper lengths to have their open extremities extend slightly beyond the last fin. The refrigerant pipes 16 and the fins secured thereto are removed from the rack after the pipes have been inserted and the rack is refilled with the same number of fins 14 as originally used. Space is left in the rack for the interposition between the fins 14 of the projecting edges of the fins 15 already assembled. The assembled section is then placed alongside the rack with the projecting edges of the fins 15 inserted into the rack between the fins 14. The

openings 18 in all of the fins 14 and 15 in the rack are properly aligned with each other. A proper number of refrigerant pipes 16 are again projected through all of the openings in the fins 14 and 15 in the rack. The assembled unit, consisting of the two sections joined together by means of the fins 15, is then removed from the rack. Any desired number of sections may be built into the vaporizer unit by repeating the foregoing operation a suitable number of times, and by using proper length fins for joining the sections together.

After the desired number of sections have been assembled as above described, the open ends of each of the refrigerant pipes are joined to the diagonally opposite ends of the adjacent pipes by the couplings 19. The margin between the outer pair of holes on each of the fins 14 is of sufficiently limited extent to permit the use of the same standard coupling for joining the extremities of pipes in adjacent fins as is used in joining the extremities of the pipes both of which are in the same fin.

This method of assembling a refrigerant vaporizer makes possible the construction of a vaporizer of any desired size from standard parts, the only additional material needed being various sized fins 15 to correspond to the desired number of sectional units to be employed. The same rack and the same means for projecting the refrigerant pipes through the fins are used on all sizes of vaporizers.

It will be apparent to those skilled in the art that the structure disclosed herein is merely illustrative of the invention and that many modifications and changes may be made in such structure without departing from the spirit of the invention or from the scope of the appended claims.

I claim:

1. A refrigerant evaporator comprising a plurality of sectional units, each unit comprising a plurality of heat transfer fins, a plurality of U-shaped refrigerant pipes projecting therethrough, and means for connecting the ends of adjacent pipes to form a continuous coil, means for rigidly and operatively connecting the sectional units together on the same horizontal plane comprising a plurality of larger heat transfer fins interposed at intervals between the sectional fins, all of the refrigerant pipes in each of the sectional units projecting through each of the said larger fins, and couplings for joining the open ends of the refrigerant pipes in each unit to the open ends of the pipes in the adjoining unit, and means for admitting refrigerant to an open extremity of one of the units.

2. A refrigerant evaporator comprising a plurality of sectional units, each unit comprising a plurality of heat transfer fins having refrigerant pipes projecting therethrough, and means for rigidly securing the units together comprising a plurality of larger heat transfer fins interposed at intervals between the sectional fins, a refrigerant pipe in each sectional unit projecting through the larger fins.

3. A refrigerant evaporator comprising a plurality of sectional units, each unit comprising a plurality of heat transfer fins having refrigerant pipes projecting therethrough, a plurality of larger heat transfer fins interposed at intervals between the first-mentioned fins for rigidly locking the sectional units together, a plurality of refrigerant pipes in each sectional unit projecting through the larger fins, and means for operatively connecting the pipes in each unit to the pipes in the adjoining unit.
